UNITED STATES PATENT OFFICE

2,400,372

FLUID PRESSURE ACTUATED VALVE

Harry N. Rider, Youngstown, Ohio, assignor to
 "Automatic" Sprinkler Company of America,
 Youngstown, Ohio, a corporation of Delaware

Application April 6, 1944, Serial No. 529,869

4 Claims. (Cl. 169—19)

This invention relates to a fluid pressure actuated valve.

The principal object of the invention is the provision of a fluid pressure actuated valve capable of use in controlling the entrance of fire extinguishing fluid to a sprinkler system.

A further object of the invention is the provision of a fluid pressure actuated valve capable of remote control.

A still further object of the invention is the provision of a fluid valve of the latched clapper type having fluid pressure actuated means for unlatching the clapper thereof.

The fluid pressure actuated valve shown and described herein has been designed to provide an efficient and simple valve construction which may be used in any fluid line for the control of the fluid flow therethrough as it may be actuated by the utilization of the fluid pressure it controls or it may be actuated by the application to the valve of fluid pressure from another source. The valve element of the fluid pressure actuated valve comprises a clapper which is held in normally closed position by means of a movable latch which in turn is adapted for actuation by a fluid pressure operated means which in turn is subject to actuation by the application thereto of suitable fluid pressure, as, for example, from a compressed gas source incorporating a remotely actuated control means, or the application of fluid pressure to the pressure operated means from the fluid line being controlled, such application of fluid pressure being subject to remote control. The control means controlling the application of fluid pressure to the valve of the invention may obviously comprise heat actuated devices which may be positioned, for example, in a fire zone.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a cross sectional side elevation of the fluid pressure actuated valve.

Figure 2 is a schematic illustration of means for applying actuating pressure from a separate source to the valve illustrated in Figure 1.

Figure 3 is a schematic illustration with parts in cross section illustrating means for applying fluid pressure from the controlled line to the valve illustrated in Figure 1.

This application is a continuation in part of my co-pending application for patent on Pressure tank sprinkler system with secondary supply, 60

No. 450,659, filed July 13, 1942 which has matured into Patent 2,353,116.

By referring to the drawing and Figure 1 in particular, it will be seen that a fluid pressure actuated valve has been disclosed which consists of a body member 10 having an inlet 11 and an outlet 12 and defining a chamber 13 in which a clapper 14 is pivotally mounted by means of a pivot 15, the clapper 14 seating upon a seat ring 16 positioned in the body member 10. A gasket 17 is positioned in the clapper 14 and is adapted to register with the seat ring 16 so as to effect a fluidtight closure. A ledge 18 is formed on the clapper 14 at a point opposite the pivot 15 thereof and is adapted to register with a latch 19 which in turn is pivoted to the interior of the valve body 10 by means of a pivot 20. An anti-reseating latch 21 is also pivoted on the pivot 20 and is held in operative position by means of a spring 22. The anti-reseating latch 21 is adapted to be moved upwardly by the clapper 14 and to prevent the clapper 14 from reseating itself on the seat ring 16 once it has opened. The latch 19 is pivotally attached to a keeper bar 23 by means of a pivot pin 24 and the keeper bar 23 passes outwardly through an opening 25 in the valve body 10 which opening 25 is closed about the keeper bar by means of a diaphragm 26. The keeper bar 23 is mounted in a central opening in the diaphragm 26. A back-up plate 27 is also positioned over the opening 25 of the valve body 10 and the outwardly extending end of the keeper bar 23 is provided with a cam construction 28 so that movement may be applied thereto for actuating the latch 19.

A housing 29 is attached to the valve body 10 by suitable means and is in registry with the opening 25 and incorporates therein a chamber 30 in which a piston 31 and a diaphragm 32 are located. A cap 33 closes the diaphragm chamber 30 and is provided with an opening 34 with which a fluid pressure conveying tube 35 communicates. A piston rod 36 surrounded by a spring extends inwardly from the piston 31 and into the interior of the housing 29 and is connected to one end of a lever 37 by means of a pivot 38. The lever 37 is pivoted by means of a pivot 39 to the housing 29 and a pair of cam shaped arms 40 formed on the opposite end of the lever are adapted to engage the cam construction 28 on the adjacently positioned keeper bar 23. It will thus be seen that fluid pressure admitted to the device through the tube 35 will move the piston 31 and rod 36 against the lower end of the lever 37. This action causes the lever 37 to pivot on the pivot 39 and the cam shaped arms 40 to engage the cam construction 28 on the keeper bar 23 so as to impart movement thereto sufficient to move the latch 19 away from the ledge 18 on the clapper 14 which permits fluid pressure in the inlet 11 to raise the clapper and flow through the valve.

It is obvious that several methods of applying fluid pressure to the chamber 30 of the fluid pressure actuated valve are possible and two such methods are illustrated in Figures 2 and 3 of the drawing, respectively. In Figure 2 of the drawing a schematic illustration of a compressed gas release mechanism such as constitutes the subject matter of my U. S. Patent No. 2,340,143 of January 25, 1944, is indicated by the numeral 41 which mechanism includes a valve 42. The compressed gas release mechanism 41 controls a compressed gas source such as a compressed gas cylinder 43 and is capable, upon actuation, as by a heat actuated device 44, of releasing the compressed gases from the cylinder 43 into a tube 35A which, in actual practice, would connect with the tube 35 heretofore described so that the compressed gases would be brought into engagement with the piston 31 of the valve heretofore described and cause the release of the clapper latch 19. The heat actuated device 44 or air thermostat comprises a sealed chamber as well known in the art and it is connected to the mechanism 41 by a communicating tube 45. The heat actuated device 44 is adapted to confine air and, when subjected to heat, to direct the expanded air through the tube 45 to the compressed gas release mechanism 41 where the same serves as the actuating medium. It will thus be observed that the actuation of the fluid pressure actuated valve illustrated in Figure 1, when utilized in connection with the compressed gas release mechanism illustrated in Figure 2, is dependent for operation on one or more of the heat actuated devices 44 which may obviously be located in a fire zone when the valve illustrated in Figure 1 is used in connection with controlling the entrance of fire extinguishing fluid to the riser 49 of a sprinkler system including distributing pipes such as that indicated by the numeral 50, a sprinkler 51 is positioned on the distributing pipe 50.

The valve illustrated in Figure 1 is also capable of actuation by the application of fluid pressure from the inlet side thereof to the piston 31 thereof and such an arrangement is illustrated in Figure 3 wherein a broken away section of a fluid supply pipe is indicated by the numeral 46 which, in actual practice, would communicate directly with the inlet 11 of the valve in Figure 1. A tubular connection 35B is subject to the control of a valve 47 and establishes communication between an opening 48 in the fluid supply pipe 46 and the tube 35 of the valve illustrated at Figure 1. The valve 47 may be any valve known in the art such as, for example, the fluid release valve and actuating mechanism comprising the subject matter of my joint co-pending application for patent, Serial Number 462,630 filed October 9, 1942. The valve 47 may obviously be capable of remote actuation as by means of suitable heat actuated devices located in a fire zone. It is understood that the valve illustrated in Figure 1 would be actuated by one or the other of the mechanisms illustrated in Figures 2 and 3 or by any other means of applying fluid pressure to the operating portions of the fluid pressure actuated valve.

Having thus described my invention, what I claim is:

1. In a fluid pressure actuated valve including a valve body enclosing a chamber having an open-

ing therein, a clapper pivotally mounted in said chamber, and a latch engaging said clapper to maintain said clapper in closed position, mechanism controlling the release of the said latch comprising a housing affixed on the said valve body and having a passage in alignment with said opening, an operating lever, means mounting said lever for motion in said housing, means engaging one end of said lever and having one end extending through said opening and pivoted to the said latch, a diaphragm chamber formed on said housing, a piston and diaphragm positioned therein and means between said piston and the other end of the said lever for moving said lever when fluid pressure is applied to the said diaphragm.

2. A fluid pressure actuated valve comprising a valve body having inlet and outlet openings, and a clapper adapted to control the passage of fluid therethrough, an opening formed in said body and a keeper bar positioned in said opening by means of a flexible diaphragm, a latch pivoted in said valve body and adapted to engage said clapper so as to retain it in seated position, the said keeper bar being pivoted to said latch, means for moving the said keeper bar and latch, said means comprising a housing affixed to the valve body in registry with the said opening, a diaphragm chamber formed in said housing, a diaphragm and piston assembly positioned in said diaphragm chamber, a lever pivoted in said housing for receiving motion of said piston and applying said motion to said keeper bar and means for introducing fluid pressure into the said chamber so as to actuate the said latch mechanism thereby.

3. A fluid pressure actuated valve comprising a valve body having inlet and outlet openings, and a clapper adapted to control the passage of fluid therethrough, an opening formed in said body and a keeper bar positioned in said opening by means of a flexible diaphragm sealing said opening, a latch pivoted in said valve body and adapted to engage said clapper so as to retain it in seated position, the said keeper bar being pivoted to said latch, means for moving the said keeper bar and latch, said means comprising a housing affixed to the valve body in registry with the said opening, a diaphragm chamber formed in said housing, a diaphragm and piston assembly positioned in said diaphragm chamber, a lever pivoted in said housing for receiving motion of said piston and applying said motion to said keeper bar and means for introducing fluid pressure into the said chamber so as to actuate the said latch mechanism thereby.

4. In a fluid pressure actuated valve including a valve body enclosing a chamber having an opening therein, a clapper pivotally mounted in said chamber, and a latch engaging said clapper to maintain said clapper in closed position, mechanism controlling the release of the said latch comprising a member engaging the said latch, a diaphragm associated with the said member for sealing said opening, and a diaphragm chamber having a piston and diaphragm positioned therein, and means between the said piston and the said member for moving the said latch to release the said clapper when fluid pressure is applied to the said diaphragm.

HARRY N. RIDER.
